UNITED STATES PATENT OFFICE

142,972

DESIGN FOR A VACUUM CLEANER CASING

George W. Walker, Pleasant Ridge, and Theodore Ornas, Birmingham, Mich., assignors to Eureka Vacuum Cleaner Company, Detroit, Mich., a corporation of Michigan

Application October 8, 1943, Serial No. 111,308

Term of patent 14 years

(Cl. D9—2)

To all whom it may concern:

Be it known that George W. Walker and Theodore Ornas, citizens of the United States of America and residents, respectively, of Pleasant Ridge and Birmingham, in the county of Oakland and State of Michigan, have invented a certain new, original, and ornamental Design for a Vacuum Cleaner Casing, of which the following is a specification, reference being had to the accompanying drawings, forming a part thereof.

Fig. 1 is a front perspective view of a vacuum cleaner casing showing our new design, the same being on an enlarged scale in comparison with showings in Figs. 2 and 3;

Fig. 2 is a rear perspective view of the cleaner casing being taken from the opposite side to that shown in Fig. 1;

Fig. 3 is a front elevational view of the cleaner casing.

The essential features of our design reside in the parts shown in full lines. The stippling shown in the drawings is for purposes of shading only.

We claim:

The ornamental design for vacuum cleaner casing, substantially as shown and described.

GEORGE W. WALKER.
THEODORE ORNAS.
